Inventor:

Fred J. Miller.

United States Patent Office.

FRED. J. MILLER, OF BROOKLYN, NEW YORK.

Letters Patent No. 80,557, dated August 4, 1868.

SPEAKING-TRUMPET.

The Schedule referred to in these Letters Patent and making part of the same.

TO ALL WHOM IT MAY CONCERN:

Be it known that I, FRED. J. MILLER, of Brooklyn, in the county of Kings, and State of New York, have invented, made, and applied to use a certain new and useful Improvement in Fire-Trumps; and I do hereby declare the following to be a full, clear, and exact description of said invention, reference being had to the annexed drawing, making part of this specification, which represents, in—

Figure 1, a section of my improved trumpet open for use, and—

Figure 2 is shown the trumpet when closed.

Similar marks of reference denote the same parts.

a is the mouth-piece; *b*, the bell. *c* is a tube, permanently attached to the mouth-piece. *d e f h i* are movable rings, made tapering, that is, smaller at the top than at the bottom. *k* is a wire, soldered around the top edge of the bell *b*. *l l* are catches, soldered to the mouth-piece. *m* is an opening in the wire *k*, which allows the catches to pass through said wire, the catches *l l* holding the mouth-piece in place, as shown in fig. 2.

Trumpets are much used by firemen and others, and when not in use occupy a great deal of room, and the object of my invention is to produce a trumpet that will be so constructed that when it is not in use can be conveniently carried in the pocket; to accomplish which I construct a trumpet in the following manner:

I make my trumpet of brass, German silver, or any other material, and form the mouth-piece *a* in the usual way, as shown in fig. 1, to which is permanently attached the tube *c*. *d* is a movable ring, being made smaller at the top than at the bottom, but larger at the top than the lower part of the tube *c*, so that when drawn down the ring *d* will slide over but not entirely off the tube *c*. *e f h i* are also movable rings, each ring being made smaller at the top than at the bottom, so that the lower part of each ring will bind tightly around the upper part of the ring just below it when the trumpet is pulled out to its full extent. The upper edge of the bell *b* is made of a size inside smaller than the outside of lower part of the ring *i*, so that it prevents the ring *i* from entirely passing through the bell. At *l*, I provide catches, which are attached to mouth-piece, and when the mouth-piece is pressed down, the catches will slip over the wire *k*, through the opening *m*, fig. 2. Then, if the mouth-piece is turned partly around, it will be held in its place by the catches *l*. At *o*, I provide a stop to prevent the movable ring from passing through the bell.

When the trumpet is required to be used, it is only necessary to turn the mouth-piece around until the catches *l* are opposite the openings *m*, and then raise the mouth-piece until all the rings are drawn out and bind tightly together, and it is then in condition to be used the same as any other trumpet made in the usual way without the movable rings or sections.

When the trumpet is to be carried in the pocket, by simply pressing the mouth-piece and bell together, and passing the catches *l* through the openings *m*, and then by turning the mouth-piece partly around, the trumpet will then be reduced to the shape and size shown in fig. 2, which will readily be seen and can be conveniently carried in the pocket.

Having thus fully described my invention, what I claim, and desire to secure by Letters Patent, is—

As a new article of manufacture, a pocket-trumpet, made in substantially the manner described and shown, and for the purposes set forth.

In witness whereof, I have hereunto set my signature, this 16th day of March, 1868.

FRED. J. MILLER.
